METHOD OF AND MACHINE FOR AUTOMATICALLY WRAPPING ARTICLES

Louis R. Muskat, Glenview, and King L. Klopfenstein, Prospect Heights, Ill., assignors to Triangle Package Machinery Company, Chicago, Ill., a corporation of Illinois

Filed July 3, 1961, Ser. No. 121,519
8 Claims. (Cl. 53—184)

The invention relates generally to methods of and machines for automatically wrapping articles, but relates more particularly to methods of and machines for wrapping articles which vary greatly in size and thickness.

As by way of illustration, and not by way of limitation, reference will be made to conditions which obtain in connection with the wrapping of articles or products in the so-called "supermarkets," where it is necessary to wrap a large number of different sizes of articles or products.

While there are machines for automatically wrapping articles or products, they are not well adapted to the needs of places such as supermarkets because of the amount of time required to change over from one size of article to another size and for other reasons. Hence, the general practice in supermarkets is to use semi-automatic wrapping equipment wherewith an operator first makes a partial wrap, usually with the aid of certain apparatus, and thereafter completes the wrap with other mechanism.

The foregoing practice is open to a number of objections.

One objection is that, because of the necessity of making a partial wrap by hand operation of the so-called "semi-wrap," wrapping is relatively slow, so that at times it is necessary to have a number of operators working to produce the first or partial wrap.

Again, because of the relatively slow wrapping operation, the labor costs are relatively high; because the skill of the operator is a factor in the quality of the wrap, uniformity is difficult, if not impossible, to obtain, and the quality of the wrap is not as high as desired.

In wrapping according to the prior semi-wrap practice, individual sheets are used, of which there is a large number. This involves carrying all such sheet sizes in stock, which imposes a substantial inventory problem.

The general object of the invention is to provide a method of wrapping articles of various sizes in a more rapid, better, and less costly manner than has heretofore been possible.

A further object of the invention is to provide a machine wherewith the method above referred to can be conveniently and efficiently practiced.

Another object of the invention is to provide a method of and machine for wrapping various sizes of articles in which a relatively few rolls of stock of different width can be used, thus reducing the cost, overcoming inventory problems, and in other ways facilitating and improving the wrapping operation.

Again it is an object of the invention to provide a method of and machine in which the quality of the wrap is not dependent upon the skill of the operator.

A still further object of the invention is to provide a method of and machine for wrapping various sizes of articles, utilizing but a few rolls of wrapping material stock of different width, so disposed that the operator can easily move the stock of any roll to article-wrapping position and, when in such position, be able to adjust the operation to wrap with such roll articles of one size and/or articles which vary in size through a predetermined range.

One of the most difficult objects to accomplish in the

2

wrapping of articles, especially when they are not of regular size and shape, is that of obtaining a tight wrap. It has been proposed heretofore to subject the completely wrapped article to a medium causing the wrapper to shrink, but this is not as effective as desired.

One of the objects of the present invention is to provide a method of and machine for applying tension to the film-wrapping material prior to the sealing operation as an aid to obtaining a tight wrap.

Various other objects and purposes of the invention will appear as the specification proceeds to describe the method of operation and mechanism for practicing the method as illustrated in the accompanying drawings in which:

FIGURE 1 is a view, partly in elevation and partly in longitudinal section, of the input end of a wrapping machine embodying the preferred form of the invention and wherewith the wrapping method can be carried out;

FIG. 2 is a fragmentary detail sectional view as taken on the line 2—2 of FIG. 1, but on a scale enlarged thereover;

FIG. 3 is a view, in side elevation, of the output end of the machine, from which the wrapped packages are discharged;

Note.—FIGS. 1 and 3, when joined at the vertical lines X—X thereon, show the full length of the machine.

FIG. 4 is a vertical sectional view through a part of the machine as taken on the line 4—4 of FIG. 3, but on a scale enlarged thereover, a wrapped package being indicated by dotted lines thereon;

FIG. 5 is a transverse vertical sectional view through the wrapped package discharge conveyor as taken on the line 5—5 of FIG. 3, but on an enlarged scale;

FIG. 6 is a plan view of that part of the machine appearing in FIG. 1 with parts broken away for illustrative purposes, as will be more fully described later;

FIG. 7 is a longitudinal vertical fragmentary sectional view as taken on the line 7—7 of FIG. 9;

FIG. 8 is a transverse vertical sectional view through the machine as taken on the line 8—8 of FIG. 1, but on a scale enlarged thereover;

FIG. 9 is a transverse vertical sectional view through a part of the machine as taken on the line 9—9 of FIG. 1, but on a scale enlarged thereover;

FIG. 10 is a diagrammatic horizontal sectional view on the line 10—10 of FIG. 9, on a reduced scale, and illustrates more particularly the endless chain and its training about associated sprockets, whereby the parts shown in FIG. 9 may be adjusted vertically;

FIG. 11 is a fragmentary view, in side elevation, of parts associated with the main drive shaft in the lower central portion of FIG. 1, but on an enlarged scale;

FIG. 12 is a horizontal sectional view as taken on the line 12—12 of FIG. 11;

FIG. 13 is a fragmentary plan elevation of the parts appearing in the lower central portion of FIG. 6, but on a scale enlarged thereover, and will be explained in more detail later;

FIG. 14 is a vertical sectional view as taken on the line 14—14 of FIG. 13;

FIG. 15 is a fragmentary plan view, on an enlarged scale, of the mechanism for moving the transverse pusher in a straight line movement between its two positions, and for moving the article or product from the input table to a position between the plates of a pair thereof, to a point in advance of the longitudinal pusher bar;

FIG. 16 is a detail fragmentary vertical sectional view as taken on the line 16—16 of FIG. 15;

FIG. 17 is a diagrammatic vertical sectional view through three sets or pairs of film-supporting plates as taken on the line 17—17 of FIG. 6, but on a scale enlarged thereover;

FIGS. 18, 19, and 20 are detail sectional views through

the sets of film-supporting plates as taken on the lines 18—18, 19—19, and 20—20, respectively, of FIG. 17;

FIG. 21 is a perspective view of a roll of the folded film strip used to provide upper and lower sections or plies thereof connected along one side or margin by a fold;

FIG. 22 is a fragmentary view in plan, on an enlarged scale, of parts appearing in the upper right-hand portion of FIG. 6, more particularly showing the parts whereby intermittent movement is imparted to the wrapped package from the longitudinal sealing station to the continuously driven chain conveyor at the output end of the machine;

FIG. 23 is a diagrammatic elevational view of the parts appearing in FIG. 22 when viewed from the lower side thereof;

FIG. 24 is a perspective view of one of the feed members or dogs employed in the structure of FIGS. 22 and 23, which will be more fully described later;

FIG. 25 is a diagrammatic view that corresponds to a longitudinal section through the upper part of the machine and particularly illustrates the passage of an article or product from the input end through the wrapping and sealing stations, heat shrinkage tunnel, and along the output conveyor;

FIG. 26 is a perspective view of the finished package product produced in accordance with the method and the apparatus of the invention;

FIGS. 27 and 28 are sectional views through the finished package of FIG. 26 as taken on the lines 27—27 and 28—28, respectively, thereof;

FIG. 29 is a perspective view of a modified form of film strip roll that may be employed instead of the form shown in FIG. 21 by using slightly modified mechanism;

FIG. 30 is a perspective view of a finished package made with two separate associated film strips appearing in FIG. 29;

FIG. 31 is a fragmentary view, in elevation, of parts associated with the pairs of film strip supporting plates for controlling the spacing between the plates of each pair and will be more fully described later;

FIG. 32 is a fragmentary vertical detail sectional view as taken on the line 32—32 of FIG. 31;

FIG. 33 is a fragmentary view, in plan elevation, of parts appearing in the central portion of FIG. 31;

FIG. 34 is a vertical detail sectional view, on an enlarged scale, as taken on the line 34—34 of FIG. 33;

FIG. 35 is a detail sectional view as taken on the line 35—35 of FIG. 32;

FIG. 36 is a fragmentary perspective view of parts employed at both the cross-sealing and the longitudinal sealing stations, the bars thereof being shown in their sealing positions;

FIG. 37 is a vertical sectional fragmentary view as taken on the line 37—37 of FIG. 36 through the longitudinal or side sealing bar and with the bars in open position;

FIG. 38 is a view similar to FIG. 37 when certain lateral stretching bars for the film margins have gripped the same and before the sealing bars reach sealing position for sealing of film margins;

FIG. 39 is an enlarged detail view of parts appearing in FIGS. 37—38, better to illustrate the gripping of the film margins before pulling thereon to stretch the film before sealing;

FIG. 40 is a view similar to FIGS. 37 and 38 showing the manner in which certain film-stretching bars have swung outwardly and away from the associated sealer bars serving to pull on the margin of the film gripped between them and operative to stretch the film and hold the same in this condition while the sealer bars engage and seal that part of the film between the article or product and the tensioning bars;

FIG. 41 is a vertical detail sectional view as taken on the line 41—41 of FIG. 40;

FIG. 42 is a top plan view of the parts appearing in FIG. 41;

FIG. 43 is a vertical sectional view through the structure for performing the cross-sealing operation on the film with certain film-stretching bars and the sealing bars in the open position for permitting relative movement between the article or product and the film, under the operation of the longitudinal bar, to a point rearward of but adjacent the cross-sealing bars;

FIG. 44 is a vertical sectional view as taken on the line 44—44 of FIG. 43;

FIG. 45 is a view of portions of the sealing and stretching bars appearing in FIG. 43 in a changed relation, as will be later described;

FIG. 46 is a view similar to FIG. 43 showing the sealing bars and stretching bars in a changed position, as when the film has been pulled or tensioned laterally and the sealing bars have moved into sealing engagement with the stretched film;

FIG. 47 is a top plan fragmentary view of the parts appearing in FIG. 46;

FIG. 48 is a diagrammatic view of the parts associated with the cross-seal film-gripping bars for moving said bars toward and away from each other in timed relation to the movement of the associated cross-sealing bars;

FIG. 49 is a detail vertical sectional view through the transverse sealing bars and film-clamping means associated therewith on the line 49—49 of FIG. 36, the sealing bars, on a larger scale, being shown in the position which they occupy as they approach the sealing and cut-off position; and

FIG. 50 is a detail vertical sectional view, through the longitudinal sealer bars and the film-clamping means associated therewith, on the line 50—50 of FIG. 36, of the sealing bars, but on a larger scale, being shown in the position which they occupy as they approach the sealing and cut-off position.

General Description of Method and Machine

40 Before proceeding with a detailed description of the steps of the method and the mechanism illustrated in the various views of the drawings, a general statement concerning the same will facilitate an understanding thereof.

The left-hand end of the machine as viewed in FIGS. 1, 17, and 25 will, for convenience, be termed the "input end" and the right-hand end (FIGS. 3 and 25), the "output end."

At A of the input end of the machine there are supported for rotation three separate shafts, each one adapted to receive a roll of film, the film being preferably in the form of a once-folded sheet, so as to comprise upper and lower sections hinged along one edge by the fold (see FIG. 21) or in the form of separate strips (FIG. 29). As a matter of convenience the folded form will be used in the description. Each roll is of different width, the greatest width roll to be used for the largest range size of packages; the second, or intermediate, width roll to be used for packages of intermediate range of sizes; and the smallest width roll to be used for packages in the smallest range of sizes.

60 The machine is designed automatically to wrap articles or products. The article or product to be wrapped is placed upon a supporting plate or table T, which is a part of the machine, on the operator's side adjacent the input end. This table or plate is maintained, as later explained, in the same plane as the lowermost of two separator plates which hold, in spaced relation, the upper and lower sections of a once-folded film.

Separator Plate Arrangement

70 At B, adjacent to but forwardly of the input end and above the several rolls of film, there are provided three pairs of separator plates. Mechanism is provided whereby the plates of each pair may be moved to and from one another whilst maintaining them in parallel relation.

Handle means C and associated mechanism are provided whereby any of the three pairs of separator plates can be swung into operative position, in which event the other two sets of plates are disposed radially outwardly of the operative position.

The functioning of one set of plates when the same is disposed in operative position will first be described, and, in this connection, the relationship of the plates to the transverse sealer and cutter will first be described.

Transverse Sealer and Cutter

Assume that a pair of plates is in operative position, in which event film from one of the feed rolls will pass upwardly over a transversely positioned freely rotatable locator roll LR, one section of the film being disposed upon the upper side of the upper plate and the other section upon the lower side of the lower plate, so that the hinge part of the film, which is along one edge, is centrally disposed between the upper and lower plates.

At D, a short distance beyond the forward end of the separator plates, are transverse sealer-cutter mechanism and transverse film-tensioning means. When the jaws of the sealer are together, the plane of contact is substantially in the same horizontal plane as the top portion of the aforementioned rotatable locator roll LR. The top of the locator roll LR and the meeting line of the sealer are always in the same horizontal plane. Also, the separator plates are always located substantially equidistant above and below this horizontal plane. This is also true no matter which pair of separator plates is in operative position.

Vertical Control (E)

Control E (FIG. 6) comprises a handwheel for providing vertical adjustment of certain of the parts whereby the turning of the handwheel results in moving the separator plates away from each other or toward each other whilst they are maintained in parallel confronting relationship, the direction of the rotation of the handwheel determining whether the movement of the plates will be toward or away from each other.

Movement of the handwheel E also simultaneously adjusts, in a vertical direction, all surfaces on which the article is supported and guided, the means for moving the article from the supporting table to and between the spreader plates, the longitudinal pusher, and the mechanism for intermittently advancing the package beyond the cross sealer to the longitudinal sealer and thence to the continuously operating output conveyor.

The article-supporting table or platform T and the lower plate of the pair of separator plates always move together so that they are always in the same horizontal plane, thus permitting the article to be wrapped to be moved laterally from the supporting table T onto the lower plate. It has already been explained that the upper and lower plates are always equally spaced from a horizontal plane in which the center line of the transverse sealer and cutter and on the top of the rotating locator LR at the input end of the machine are located. Since the lower plate and the supporting table or platform move together, it is obvious that the product or article platform, likewise, is disposed the same distance below the said central horizontal plane as the upper plate is disposed above that horizontal plane.

Bridge Plate and Extension Rails

Between the transverse sealer and cutter and film tensioner at D and the forward ends of the pair of plates, there is disposed a bridge plate P, the upper surface of which is in the plane of the upper surface of the lower separating plate and article-supporting platform. This bridge plate extends transversely of the machine and spans the distance between the forward edges of the separating plates and the adjacent transverse sealer and cutter at D.

Forwardly of the transverse sealer and cutter there is disposed a pair of extension rails R, the upper surfaces of which are disposed in the same plane as that of the bridge, the extension rails moving up and down so as to maintain them in the same plane as the lower product-supporting plate, bridge plate, and product-supporting table or platform, all of which, as before generally explained, are controlled by the movement of the handwheel E.

Control G

Control G comprises a wheel mounted on a horizontally disposed shaft. Rotation of wheel G in a clockwise direction moves the rail closest to the operator and certain associated mechanism away from the fixed rail at the far 15 side and also moves the longitudinal sealer bar assembly (to be described later) with it.

As the movable extension rail is moved toward or away from the fixed rail, linkage also moves a pusher member which is mounted for supplying movement on the article-supporting table in a direction toward and away from the separator plates. In this way the pusher member, movable extension rail, and longitudinal side seal are synchronized to move together, so that when adjustment is 20 to be made for the width of the package these members will all be properly positioned for operation.

Spaced between the movable extension rail and that side of the machine closest to the operator is a longitudinal side seal device SS having jaws which open and close 25 at the proper time to seal the two marginal edge portions 30 of the upper and lower sections of the sheet together and also to sever any excess film which extends in a direction away from the package and toward the operator's side of the machine. The amount of severed film will depend upon the size of the package and the width of the particular film roll then being used. Just before the longitudinal sealing operation takes place, mechanism functions 35 to tension the film sections by pulling outwardly (toward the operator's position) on longitudinal portions of the film adjacent the zone where the longitudinal seal is to 40 be made.

When the product or article to be wrapped is placed on the supporting table and the machine is in operation, the pusher member described above pushes the product into 45 position between the upper and lower separator plates (the product resting on the upper side of the lower separator plate) and then retracts to its position on the table to permit placement of another article or product on the product-receiving platform or table.

Longitudinal Product-Pushing Arm

It will be understood that when the product or article 50 to be wrapped is in position resting on the lower separator plate means are provided for moving the product longitudinally of the machine and toward the transverse 55 sealer and cutter. At this time, due to a previous action of the transverse cutter and sealer, the two forward marginal edge portions of the upper and lower sections of the film will have been cross sealed. Hence, when the longitudinal article pusher arm starts moving forwardly, 60 which is accomplished by means of properly timed mechanism, the trailing end of the article is engaged and pushed forward until the cross-sealed part of the film sections is engaged, whereupon the film and article move together to a position where the trailing end of the article is forwardly of the transverse sealer and cutter bars, whereupon the longitudinal pusher member reverses its movement, moving backwardly into a position between the upper and lower separator plates and the two jaws of the transverse sealer and cutter are brought into contact, thus 65 causing a transverse sealed zone, which zone, of course, is then located adjacent the trailing end of the package which is forwardly of the sealer and forwardly of the bridge plate. It should be understood that just before the transverse seal is effected a transverse tensioning of 70 the film adjacent the transverse sealing bars takes place.

As soon as the sealing takes place, cutting also occurs transversely and intermediate of the sealed zone, whereupon the sealing jaws separate, leaving the forward package transversely sealed along both ends, but leaving a longitudinal margin of each section unsealed. However, the longitudinal sealing of these marginal portions occurs by virtue of a pair of sealing jaws similar to the transverse sealing jaws but, as before explained, disposed longitudinally of the machine and parallel to the extension rails. The longitudinal sealing jaws are properly timed with respect to the transverse sealing jaws so that as soon as the package is completely sealed it can be moved forward by mechanism which engages the trailing end of the package. It should be understood that just prior to the time the longitudinal seal is made the film is pulled laterally to remove slackness, and the same mechanism separates the waste film after sealing and cut-off.

The mechanism for intermittently advancing the package comprises dogs which, at one time, project upwardly above the plane of the rails, then at the forward part of the stroke move downwardly and rearwardly, again moving upwardly to engage the next package. The dogs referred to move the said package forward to a position where another endless chain will move the now fully wrapped package through a heat chamber where shrinkage of the film occurs.

The heating chamber may be of conventional construction and consists generally of electrical heating units over which air is blown, the heated air discharging onto all of the superficial area of the wrapped package, thus causing the film to shrink so that when the package emerges from the heating chamber the film will be tightly stretched, or in a taut condition, around all of the parts of the wrapped package, thus presenting a very neat, compact package.

As before explained, there are always ready for use all three pairs of separator plates, each pair with its film disposed properly thereon, so that it is only necessary that if a given package is to be wrapped and is of such size that it cannot be accommodated within the size range of that particular size of separator plates then in operable position, either of the other two pairs of separator plates can be instantly swung into operative position, as may be necessary.

The specification will now proceed to describe the specific mechanisms disclosed in the drawings.

Means for Mounting Film Rolls

At the input end of the machine three separate rolls 60, 61, and 62 of the film stock such as shown in FIG. 21 are mounted, each on an associated shaft 60', 61', 62'. These shafts are supported for rotation in bearing members or arms 63, 64, 65 which are rigidly secured to and extend from the machine framing structure 66. As will be explained later, the film material is pulled from the rolls by the advancing article being wrapped between the separator blades, causing the rolls to rotate. In order to prevent over-running of the rolls, brake mechanism is provided as shown in FIG. 6 at 67. The brake mechanism presses constantly against the shaft on which the particular roll of stock is mounted. As this is or may be of conventional construction, no detailed description is thought necessary.

Separator Plates and Certain Associated Mechanism

Mounted adjacent the input end of the machine are three pairs of separator plates and mechanism whereby any selected pair thereof can be moved into operative position and also whereby the upper and lower plates of any given pair that is in operative position at the time can be moved toward or away from each other. This mechanism is best shown in FIGS. 1 and 31 to 35, inclusive. It comprises a vertical plate member 70 which is pivoted for swinging movement on a horizontal cross shaft 71 journaled in upstanding part of the machine

frame. By means of the handle 72, the plate 70 can be swung into three different positions, as indicated by the full line position and the two dotted line positions in FIG. 1. The handle 72 carries a detent which engages in holes in the frame to hold the plate 70 and parts carried thereby in any set position.

Each pair of separator plates is supported from the movable plate 70 by means of an inwardly extending bracket 72' bolted to the inner face of plate 70 (see FIG. 33). Journaled in the plate 70 and bracket arm 72' are two transversely disposed shafts 73—74. Since the mechanism for moving the selected pair of plates, when in operative position, is alike for each pair, a description of one mechanism will suffice for all. For this reason, the same numbers have been given to like parts of each set.

Fixed to shaft 73 so as to turn therewith is a bell crank member 75 having arms 76 and 77. Arm 76 is attached to cross shaft 78c which extends between spaced pieces 78 which are fixed to the bottom side of the upper separator plate. Fixed to the shaft 73 is another member or arm 81 which is also connected to a cross shaft 82c that is supported in members 82 which are fixed to the upper surface of the lower separator plate 80 similar to the manner in which the members 78 are fixed to the upper separator plates 79.

Also fixed to the shaft 74 are pairs of arms 85, 86, one pair at each side, the outer ends of which are journaled on the cross shafts 90 and 91 which extend between and are supported in the members 78 and 82, respectively.

Extending between cross shafts 90 and 82c is a tension spring 93 which tends to move the upper and lower plates together against means which cause positive separation of the plates, as later described.

Also associated with each pair of separator plate mechanisms are two intermeshing gears 94 and 95 which are fixed to shafts 73 and 74, respectively, and which function when a pair of separator plates is in operative position to cause movement of the separator plates toward and away from each other, depending upon the direction of the turning movement of the shafts 73—73 as actuated by means of the handwheel E, and certain associated mechanism which will be described later.

Description of the Means Whereby the Plates of a Pair of Separator Plates When in Operative Position Can Be Moved Toward and Away From Each Other

As is perhaps best shown in FIG. 31, the outer end of arm 77 of bell crank 75 has a roller 77' carried thereby which is in operative contact with a cam portion of member 100, when a given set of plates is moved into operative position. The cam member 100 is vertically disposed and is carried by a support 101 which, as will be later explained, can be raised and lowered by means of the said handwheel E and associated mechanism.

When a pair of plates is in operative position, as is the intermediate pair in FIG. 31, the roller 77' on arm 77 is disposed in the cam groove 103 which, it will be noted, is angularly disposed. When the roller is in the uppermost part of groove 103 the plates, through the mechanism before described, are moved to the widest spaced relationship against the action of spring 93. When the cam 100 is raised the plates are moved progressively closer together because the roller moves through the groove 103 causing swinging movement of the bell crank 75.

The function of surfaces 104 and 105 is to guide the roller of the bell crank 75 into position in the slot 103 when the separator plates of any given pair thereof are moved into the operative position.

Wrapper Film and Separator Plate Co-Action

The wrapper film of roll 61' as is shown in FIG. 21 comprises upper and lower sections 108 and 109 resulting from the fold 107. Since each roll is alike except for

width, a description of the manner in which the film sections are disposed with respect to the separator plates will suffice for all.

As is shown in FIGS. 1 and 17 the film passes under roller 110, over roller 111 and thence over the top of the locator roll LR. The top of the roll LR is in a plane intermediate the upper and lower separator plates 79 and 80, respectively.

Section 108 of the film is disposed on the outer face of plate 79 and the section 109 of the film is disposed on the outer face of the plate 80 with fold 107 opening up to accommodate the spacing between the plates of the pair as is shown in the cross-sectional views FIGS. 18, 19 and 20. As shown, the plates are horizontally disposed when in operative position so that plate 79 is sometimes termed "upper plate" and plate 80, "lower plate."

While the manner of actuating the plates is alike and the way in which the film sections are disposed with respect to the plates is the same, it will be noted that, in each instance, the lower plate is of the same width whereas the upper plate of each two pairs is of a different width. The purpose of having the lower plate of uniform width is so that the edge closest to the operator's side will be closely adjacent the plate or table on which the article or product to be wrapped is positioned. This facilitates transfer of the article from the table to a position on the upper surface of the lower plate.

Article-Receiving Table T and Associated Mechanism

The article receiving table T (see FIG. 8) comprises a horizontal plate 120 supported on an underlying member 121 which forms a part of the supporting structure that serves to support the bridge P, the rails R, and other parts as later explained.

Structure 121 is movable in a vertical direction by means of a plurality of vertical screw members, one of which, 122, is shown in FIG. 8 closely associated with table T. Two other vertical screws 123 and 124, associated more closely with other vertically movable mechanism will be described in detail later, all being actuatable by turning the handwheel E and through chain mechanism 125 and through sprockets 126, 127 and 128 turning the respective screws, causing them to rise or fall and to raise and lower the structure 121.

Referring now to FIG. 8, sprocket 127 is captive so that when it is turned the screw 123 raises or lowers and through structure 121 raises and lowers plate 120.

The cam 100, previously described in connection with separator plates, is fixed to move up and down with the table T which serves to maintain the lower separator plate always in the same plane as the plate 120 of table T.

For moving the article from its position on the plate 120 to a position on the lower plate 80 of the pair of separator plates, there is provided a transverse pusher bar and means for moving it from its full line retracted position to the dotted line extended position shown in FIG. 15. This means comprises a vertical rock shaft 131 to which is affixed one end of an arm 132, the other end of which is attached to an actuator rod 133. Also affixed to the rock shaft 131 is a link 134, the other end of which is pivotally attached at 135 to an intermediate portion of a link 136. The link 136 has one end connected at 137 to a bracket member 138, the latter being attached to the transverse pusher bar 130, extending at right angles thereto. A companion link 139 is pivotally connected at 140 to bracket 138, the other end being pivotally connected at 141 to a plate 142 which interconnects adjacent ends of links 136 and 139. The adjacent end of link 136 is pivotally connected at 143 to plate 142. Pivot 143 includes a stud shaft which extends downwardly through plate 142 and carries a roller 144 at its lower end. At 145 is a stud shaft which is carried by plate 142 and which has a roller 146 at its lower end. Rollers 144 and 146 have longitudinal guided movement in channel 147 of the member 148. Member 148 is affixed to bar 149 which is a part of the sub-framing and which, as before

explained, is raised and lowered by turning the handwheel E.

For moving the rod 133, one end thereof is connected at 150 to a cross shaft 151 which is mounted in upstanding end portions 152-152' of a bracket 153 (see FIGS. 15, 16).

Bracket 153 is carried by the upper end of arm 154 of a bell crank lever mounted for rocking movement on a cross shaft 156 (see FIGS. 1 and 11). The lower end of arm 157 of the bell crank carries a roller 158 which rides upon the periphery of cam member 160. A tension spring 161 urges the upper arm 154 in a counterclockwise direction to maintain contact of the roller 158 with the cam 160. The spring 161 causes longitudinal movement of the link 133 to the left, as viewed in FIGS. 1 and 15, and cam 160 causes longitudinal movement in the opposite direction. The result is to swing arm 132 between full and dotted line positions as shown in FIG. 15. Such movement also results in moving the transverse pusher bar 130 in a straight line movement between the full and dotted line positions as best shown in FIG. 15.

In order to locate the bar 130 in its desired initial operating position, transversely of the table plate 120, the following mechanism is used.

Handwheel G is affixed to a cross stud shaft 170 mounted for rotation in the machine main frame.

Fixed on and rotatable with shaft 170 are two sprockets 171 and 172 also mounted for rotary motion in the main frame. At a higher elevation is a shaft 173 having a threaded portion 174 intermediate its ends. Mounted on the threaded portion 174 is a nut 175 which travels along the screw when the screw is rotated by means of the handwheel G. Movement is imparted to shaft 173 by means of an endless chain 176 operating over sprockets 177 and 178 fixed to shafts 170 and 173, respectively.

Adjacent the input end of the machine and in the plane of shaft 170 is a shaft 180 mounted for rotation in the main frame. Shaft 180 has a threaded portion 181 like the threaded portion 174 of shaft 173. Mounted on the threaded portion 181 is a bracket 182 which travels along the screw portion 181 when shaft 180 is rotated. At the inner end of shaft 180 is fixed a sprocket 184 aligned with sprocket 172 of shaft 170 and driven thereby by an endless chain 185. One end of bracket 182 is fixed to the part 149 of the sub-frame.

The part 149 is mounted in the sub-frame for straight line guided movement transversely of the sub-frame by means best shown in FIGS. 13 and 14. At the right-hand end of part 149, as viewed in FIG. 14, is an L-shaped member 190, a vertical leg portion 191 being affixed to the member 149, and the horizontal leg portion 192 operating in a groove 193 formed in part 195 of the sub-frame. L-shaped bracket 190 is connected by means of member or link 196 to a vertical plate 197 which is affixed to a sleeve 198 sliding on crossbar 200, being splined to the bar to prevent turning movement. Bar 200 is fixed to the top ends of two vertical shafts 122 and 124 by which the sub-frame is raised and lowered by means of handwheel E and associated mechanism.

For moving plate 197 a link 201 is provided, one end being connected to nut 175 at 202 and the other end to the plate 197 at 203.

From the foregoing, it is evident that turning of the handwheel G causes transverse movement of the L-shaped bracket 190 and the adjacent end of part 149 of the sub-frame to which it is attached. Also, like movement of the other end of the sub-frame part 149 is caused by movement of the bracket 182 before described.

Thus, the part 149 is moved in and out in order to position the pusher bar 130 at the correct distance laterally with respect to the particular width size of the article to be wrapped, so that, when the transverse pusher bar operates automatically during a cycle of operation, it will push the article into the correct position between the upper and lower separator plates 79 and 80 with the laterally ad-

vancing side over against the fold part of the film and the laterally trailing side in such position as to provide free margins of the film extending in the direction of the operator. Such free margins, as later explained, are necessary for longitudinal sealing.

Mechanism for Operating Longitudinal Pusher Bar

The means for operating this mechanism is best shown in FIGS. 1, 2, 8, 11 and 12. The pusher bar 210 normally extends transversely of and between the separator plates 80 and 78, being relatively close to the upper surface of the lower plate. It is mounted for swinging movement on a vertical pivot 211 which pivot is carried by a sleeve 212 slideable on the longitudinal rod 213. One end of the rod 213 adjacent the input end is connected to a plate 214 which is a part of the sub-frame, the other end being connected to a similar plate 215 which is also a part of the sub-frame.

For reciprocating the sleeve 212, there is provided arm 216, the lower end of which carries a roller 217 guided for straight line movement between spaced members 218. A lever 220 is pivoted at 221 to a part of the main frame, its upper end being pivotally connected to one end of a link 222, the other end of the link 222 being connected at 223 to the arm 216 (see FIGS. 1 and 2).

To impart swinging movement to the lever 220 there is provided a cam 225 fixed to rotate with the shaft 227 which constitutes the main drive shaft, and on which the previously mentioned cam 160 is also mounted.

Arm 220 carries roller 228 which rides on the cam 225 being held in contact with the cam by means of the spring 229, one end of which is secured to a stationary part of the machine frame at 230, the other end being connected to a U-clip 231 carried by lever 220 (see FIGS. 11 and 12).

Pusher bar 210 is manually swingable about the pivot 211 from a position transversely of and between the separator plates to a longitudinal position, indicated at 210' in FIG. 6, which is outside the separator plates.

This permits any pair of separator plates to be moved, as by means of handle 72, into or out of operative horizontal position without interference. The pusher bar 210 is held by friction in either of the two placed positions just referred to.

It should be understood that the throw of the lever 220 is such that it moves the bar 210 from the position shown in FIG. 6 to a position beyond the cross-sealer mechanism when the same is in the open position shown in FIG. 43, which also is in advance of the bridge plate P (see FIGS. 1 and 6 for position of bridge plate). The bridge plate P is mounted on an upright member 232 which is a part of the sub-frame and hence moves up and down with the sub-frame, being maintained always in the same plane as the lower separator plate which is in operative position at the time.

For driving the main shaft 227, there is provided an electric motor 235, best shown in FIG. 8, by means of pulley 236 and belt 237 which drive pulley 238 of the reduction gear 239 which drives the main shaft 227 at desired speed.

Also mounted on the main drive shaft 227 is a third cam 240 which, as will be later explained, actuates both the transverse and longitudinal sealer bars.

Mechanism for Operating Transverse and Longitudinal Sealer Bar

Referring first to FIGS. 1 and 3, when placed together at line X—X in said figures, they comprise the full length of the machine.

Adjacent the bottom of the machine and extending longitudinally is a horizontal bar member 250 pivoted to the ends of which are two upstanding bars 251 which, as later explained, function to actuate the longitudinal sealer bars.

Pivoted to bar 250 at 253 is a member 254, the other end of which carries a roller 255 which rides against cam 240. Member 254 is pivoted at 256, intermediate its ends, in a bracket 257 affixed to the main frame. Member 254 includes, as an integral part thereof, an upstanding arm 258. On shaft 156 is mounted, for rocking movement, a bell crank, one arm, 259, of which is pivotally connected at 260 to a link 261, the other end of link 261 being pivotally connected at 262 to the upper end of arm 258. Arm 263 of said bell crank is pivotally connected at 264 to the lower end of a short upstanding member 265, the latter being affixed to the lower end of a yoke-shaped structure 266. The yoke structure includes upwardly and outwardly diverging arms 267 which merge into parallel portions 268, the upper ends of which are pivoted at 269 to longitudinal link members 270. The front ends of the links 270 are pivoted at 271 to upstanding plates 272 which plates are supported from a cross member 273 affixed to the sub-frame so as to move up and down therewith when the sub-frame is adjusted vertically.

The rear ends of links 270 are attached to opposite ends of the upper transverse sealer bar 275. The lower transverse sealer bar 276 is affixed to the ends of links 277 pivoted at 278 to plate 272. The front ends of links 277 are pivoted at 279 to the lower end of a link 280, the upper end of which is pivoted at 281 to the link 270, as is well shown in FIG. 43 in which the sealer jaws are in open position, the closed position being best shown in FIG. 46.

It will be evident from the foregoing that through the mechanism just described the transverse sealer bars can be swung between open and closed relation in proper sequential order.

Swinging movement of the longitudinal sealer bars is caused through the medium of the aforementioned upstanding members 251 and 252 (see FIGS. 1 and 9). The upper ends of members 251 and 252 are pivoted at 285 to an intermediate portion of the links 286, one end of which is pivotally secured at 287 to upstanding plates 288 which are mounted to move up and down with the sub-frame but are capable of movement laterally thereof. To permit such lateral movement, the bottom ends of the plates 288 have slided guided movement between longitudinally spaced rails 289.

The rails 289 are supported by a plate 290 which is fixed to and rises from a part 291 of the sub-frame.

The other ends of links 286 are affixed to opposite (front and rear) ends of the upper longitudinal sealer bar.

The lower longitudinal sealer bar 293 is affixed at its ends to links 294 pivoted at 295 on plates 288. Links 294 have offset end portions 296. Extending between portion 296 and link 286 is a member 297 which is pivotally connected at 298 to the link 286 and at 299 to offset portions 296 of links 294.

From the foregoing it should be obvious that up and down movement of members 251 and 252 will cause swinging movement of the longitudinal sealer bars between the open and closed positions, as illustrated by means of dotted and full lines, respectively, in FIG. 9.

Film-Clamping Mechanism Associated With Transverse and Longitudinal Sealing Bars

The mechanism for actuating the transverse and longitudinal sealing bars has already been described. It should be understood, however, that the sealer bars have associated with them certain other mechanism that functions in connection with the sealing operation. This mechanism and its function will be best understood by reference to FIG. 49, for the transverse sealer, and FIG. 50, for the longitudinal sealer.

Referring first to FIG. 49 the upper bar 275 has along its bottom surface a pair of spaced heating elements 300 in the form of strips between which is a single "hot" wire 301 which serves as the cut-off means and which is in a

plane below that of the strips 300. The upper surface of the lower cross-sealer bar 276 is provided with a resilient insert 302 against which the hot cut wire engages and into which it is yieldingly received in a sealing operation. So much of the sealing bars is conventional in machines for sealing film by heat and pressure. Such film is used in connection with the present method and machine.

Associated with the sealer bars 275 and 276 is additional mechanism for the purpose of clamping the two sections 108 and 109 of the film transversely on the trailing and advancing sides of the sealing bars. This mechanism comprises a U-shaped inverted channel 303 associated with the upper sealer bar 275. The leg portions 304 of the channel extend downwardly normally terminating in a plane below the bottom surface of the sealing bar. The cross portion 305 of channel 303 has thereon an upstanding sleeve 306 slidable on a stem 307 which is anchored at its bottom end in the bar 275 and which has its upper end extending into a cap 308 having a screw 309. An expansion spring 310 is positioned between the cap and the sleeve 306 and functions to press channel 303 downwardly.

The lower bar 276 is provided with solid extension members 311 which are vertically aligned with the leg portions 304 of the channel 303. When the sealing bars approach the sealing position, the lower edges of the legs 304 and the upper surface of the lower sealer bar with its associated members 311 clamp the interposed portions of the film sections 108 and 109 together before the wire 301 and the sealing strips function. This is possible because, as the lower edges of the leg portions 304 engage members 311, further movement of the sealing bars toward each other into sealing and cutoff position forces the channel 303 upwardly against the action of the spring 310. As the bars 275 and 276 separate, the channel 303 returns to its normal position.

Associated with the longitudinal sealer bars 292 and 293 is additional mechanism for the purpose of clamping the free margins of the two film sections 108 and 109 prior to the sealing and cutting operation.

This mechanism comprises an L-shaped member 315 which has a leg portion 316 that extends downwardly along the inner face of the upper sealer bar 292 normally terminating in a plane below the bottom surface of the associated sealer bar.

The cross portion 317 of the L-shaped member 315 has thereon an upstanding sleeve 318 slidable on a stem 319 which is anchored at its bottom end in the bar 292 and which has its upper end extending into a cap 320, there being a screw 321 on the stem 319. An expansion spring 321' is positioned between the cap and the sleeve and which functions to press the L-shaped member 315 downwardly.

The lower bar 293 is provided with a solid extension member 322 the inner face of which is vertically aligned with the leg 316 of the L-shaped member 315. When the sealing bars approach the sealing position the lower edge of leg 316 and the upper surface of the lower sealer bar with its associated member 322 clamp the interposed film sections 108 and 109 together before the wire 323 and the sealing strips 324 function. This is possible because, as the lower edge of the leg 316 engages the extension 322, further movement of the sealing bars toward each other into sealing and cut off position forces the L-shaped member 315 upwardly against the action of the spring 321'. As the bars 292 and 293 separate, the L-shaped member returns to its normal position.

As in the case of the lower sealing bar for the transverse sealing operation, the lower bar 293 includes a resilient cushion strip which functions in like manner. This is strip 325.

FIGS. 43 and 46 are descriptive figures, FIG. 43 showing the fully open position of the transverse sealer bars and FIG. 46 showing the fully closed position.

FIGS. 37, 38 39 and 40 are descriptive views showing 75

the longitudinal sealing bars in various positions, FIG. 37 showing the fully open position, FIG. 40 the fully closed position, and FIGS. 38 and 39 an intermediate position. In FIG. 39, the parts shown are certain of those shown in FIG. 38, but on a larger scale better to show the relationship of the parts in that stage of the sealing operation.

Associated with both the transverse and longitudinal sealing mechanisms there is means for tensioning the film section which appears in various views which have been described with respect to the clamping and sealing operation but which have not been mentioned in connection with certain film-tensioning operations which occur just prior to the sealing operations.

Tensioning or Slack Removal Mechanism Associated With the Transverse Sealer Means

Referring particularly to FIGS. 1 and 43-48, inclusive, on the main drive shaft 227 in an end portion which is supported by the vertical bracket 330 (see FIG. 48) which is mounted in the main frame of the machine, are cams 331 and 332, respectively, which rotate with the main drive shaft 227. Mounted to rock with the shaft 333, which is supported in the bracket 330, are two rocker members 334 and 335. Functionally, these members act as bell cranks. On the lower arm portion of member 334 is a roller 336 riding on the cam 331 being held thereagainst by spring 337, one end of which is anchored to the part 338 of the main frame at 339, the other end being attached to the arm portion 340 of the member 334 at 341. Member 335 carries a roller 342 which rides against the cam 332 being spring pressed by means of spring 345 which is connected to part 339, before-mentioned, and to the other arm portion of 335 at 346.

Mounted for vertical reciprocation in portion 347 of the main frame (see FIG. 48) are two vertical actuator bars 348 and 349.

Mounted for rocking movement on stud shafts 350 and 40 351 are bell cranks 352 and 353, respectively. Arm 352' of crank 352 has a bifurcated end which straddles a pin 354 fixed to the rod 349 whereby swinging movement of its bell crank causes vertical reciprocation of the rod 349.

In a similar manner bell crank 353 has a bifurcated end portion operatively engaging a pin 355 affixed to the rod 348 whereby, when the bell crank is rocked, vertical reciprocation of the rod 348 results.

For imparting rocking motion to the bell cranks 352, 353, there are links 356 and 357, respectively, which extend between and are connected at their ends to the respective members 334, 335 and bell cranks 352, 353.

From the arrangement shown and described it will be obvious that while both rods move vertically they do so in opposite directions.

As is best shown in FIGS. 43, 44 and 47, the upper ends of the rods 348 and 349 are connected to actuate upper and lower transverse bars 360 and 361, respectively. The connection between rod 348 and upper transverse bar 360 is by means of the L-shaped member 362, and the connection between the rod 348 and the lower bar 60 361 is by means of the L-shaped member 363.

Mounted on the face 360' of the bar 360 adjacent the fold side of the film is a vertically reciprocable member 370 having a vertical slot 371 therein through which project upper and lower headed pins 372 and 373, respectively. A spring 374 is connected to an offset upper portion 375 and to the lower head pin 373 whereby the spring tends to move the member 370 downwardly relative to the bar 360. The lower portion of member 370 terminates in a presser foot 376 provided with a resilient facing 377.

Associated with the lower bar member 361 and in vertical alignment with the member 370 is a similar member 370' mounted for vertical reciprocation relative to the bar 361. Since the construction and function is similar,

like parts, though inverted, have been given the same numbers primed.

Thus it is obvious that when the bars 360, 361 are moved toward each other by means of the rods 348, 349 and associated mechanism, the presser foot portion 376, 376' of the members 370, 370' first engages the upper and lower film section just forwardly of the bridge P and adjacent the fold side of the film and finally clamps such film portions of the sections therebetween.

Mounted adjacent the free end of bar 360 and on the face 360' thereof, which confronts the transverse sealer bar 275, is a flat plate 380 having a pair of spaced parallel diagonal slots 381 held in position on the bar 360 by means of headed studs 382 on the shank portion of which the plate 380 is slidable. A spring 383 connected at 384 to plate 380 and at the other end at 385 to a pin fixed in the bar 360 serves to urge the plate 380 toward the left in FIG. 44, thus causing the lower edge of plate 380 to be positioned in a plane below the lower edge of the bar 360.

A similar plate and spring arrangement, except that the same is inverted, is provided on the lower bar 361, for which reason similar parts and portions bear like numerals primed.

As is clear from FIG. 44, the lower edge of plate 380 is above the uppermost plate 77 of the separator plates and the upper edge of the plate 380' is below the lower separator plate 80.

The timing of the cams which actuate the bars 360 and 361 on which the plates 380 and 380' are mounted and the cams which actuate the sealer bars 275 and 276 are such that the confronting edges of the plates 380 and 380' engage the film sections before the sealing bars function to seal the sections together.

Because of the arrangement just described, continued movement of the bars 360 and 361 toward each other causes the plates 380 and 380' to move outwardly toward the free end of the bars 360, 361.

At the same time, plate 381 moves upwardly relative to bar 360 and plate 380' moves downwardly relative to bar 361.

As before explained, the foot portions 376 and 376' have earlier clamped upper and lower sections of the film adjacent the fold so that such portions are held against movement in any direction. However, those transverse portions of the film sections which are later clamped between the edge portions of the plates 380 and 380' are free to move laterally away from the portion clamped between the members 370, 370' which is to the right as viewed in FIG. 44. Such movement of plates 380 and 380' tensions the film, or, stated in other words, removes any slack which is present in the film section away from the fold. The amount of movement of the plates 380 and 380' is indicated by the arrowed line in the upper right-hand corner of FIG. 44, which is adequate to remove any slack normally present.

Tensioning or Slack Removal Mechanism Associated With the Longitudinal Sealing Means

Referring particularly to FIG. 37 at the end of lever or arm 286 at 400 is pivoted a segmental member 401 disposed inwardly of the arm 286. A spring 402 is anchored to segment 401 at 403, the other end being anchored at 404 to a stud carried by the bar 286. The spring 402 tends to swing the segment 401 in a clockwise direction until adjustable stop 405, carried by the segment, engages the top edge of member 286.

Longitudinally disposed bar 406 has end arms 407 which are pivoted at 408 on the segment 401 radially outward of the pivot 400. A spring 409 has one end affixed to the segment 401 at 410, the other end being affixed to the bar 406 at 411. It will be understood that there are segments and associated parts similar to those described at the opposite end of the bar 406, as best appears in FIG. 36. The lower face of bar 406 has a

groove 412 therein to receive a tongue portion on a co-acting lower bar, shortly to be described.

The spring 409 functions to swing arm 407 in a counter-clockwise direction until the upper end beyond pivot 408 contacts a stop 407x carried by the inner face of segment 401.

Associated with the arm 294 which carries the lower sealer bar is a bar 406' similar to bar 406 previously described, except that it is provided with a tongue 412' adapted to enter the groove 412 of bar 406 when those bars are in mating relation as shown in FIGS. 38 and 39.

Associated with the bar 406' are segments, spring stops, etc., which function like similar parts associated with bar 406 and segment 401, except that the parts are inverted, for which reason similar parts are given the same numerals primed.

As arms 286 and 294 swing toward each other, bars 406 and 406', together with the respective segments 401 and 401', swing toward each other. In this movement the bars 406 and 406' first come into engagement with the margins of the upper and lower segments of the film. So finally, as shown in FIG. 38 (and on a larger scale in FIG. 39), the tongue 412' on the bar 406' forces the interposed film segments into the groove 412 of the bar 406, thus firmly gripping the film margins. This action occurs before the sealing bars function to seal the margins between the wrapped article and the bars 406 and 406'.

When the members 286 and 294 reach a position closely adjacent their lowermost position, but before the sealing bars have functioned to seal the film, the springs 409 and 409' function to swing the arms 407 and 407' together with the bars 406 and 406' from the position shown in FIG. 38 (and 39) to the position shown in FIG. 40, being limited against further movement by a stop 415 carried on the inner face of arm 294. The reason the springs 409 and 409', which are weak relative to springs 402 and 402', function to move the bars 406 and 406' away from the sealer bars is that as the pivots 400 and 400' move toward each other, they bring pivots 408 and 408' in vertical alignment with the groove and tongue 412 and 412', it being understood that swinging movement of the bars 406 and 406' in the opposite direction is limited by the adjacent sealer bars. In the course of such movement, pivots 408 and 408' swing in opposite directions around pivots 400 and 400'.

The stop 415 has a portion 415' spaced inwardly of the arm 294 at one end only, the face 415' being the portion against which the bar 406' abuts. The purpose of spacing portion 415' of the stop away from the inner face of member 294 is to accommodate a portion of the segment 401' when in the position shown in FIG. 37.

This swinging movement of bars 406 and 406' acts first to tension or take up the slack of the film by pulling outwardly on the margins and after the sealing bars have functioned to seal and cut the film section, function to move the severed film away from the sealed film as shown in FIG. 40.

In the further cycle of the operation, when the bars 406 and 406' separate or move apart, the waste film stock is released and drops.

Article-Supporting Rails and Actuating Means

The manner in which the wrapper for the article has been cross-sealed and provided with a longitudinal seal has already been described. At the time of these sealing operations, the article, with its wrapper first cross-sealed, then longitudinally sealed, rides upon longitudinal rails referred to by reference R, best shown in FIGS. 6 and 9.

It will be understood that the article is, when between the separator plates, advanced by the longitudinal pusher bar. The advancing end of the article engages the cross seal of the wrapper and, as the pusher bar continues its forward movement, pushes the article and advances the

article and cross seal just mentioned until the trailing end of the article has been advanced to a position forward of the cross-seal bars. In this advancing movement the article acts to pull the film sections from the supply roll which cannot overrun because of the braking mechanism before described.

The rails R comprise an outer section 420 and an inner section 421 which best appear in FIG. 9. The outer section 420 comprises a vertical plate 422 fixed to a member 423 which is a part of the sub-frame, said part being supported by the bar 260 so as to move up and down therewith, but does not move longitudinally of the bar 260.

Below the upper end of plate 422 is a horizontal ledge 424. Attached to plate 422 by member 425 is a vertical plate 426 having an out-turned portion 427 in the plane of ledge 424, terminating short thereof so as to provide a slot 428.

The inner rail section 421 comprises a vertical plate 429 which is fixed to and moves with sleeve 193. The upper end of plate 429 terminates in an outwardly extending ledge 430 which is in the same horizontal plane as the ledge 424 of the outer section 420. The inner section 421 also includes a vertical plate 431 which is attached to plate 429 by a member 432. Plate 431 terminates at its top in an inwardly extending flange 433 in the plane of the ledge 430, terminating short thereof to provide a slot 434.

It is obvious from the foregoing that when the sleeve is moved longitudinally of bar 260 the rail 421 will move toward and away from the rail section 420 depending upon the direction of movement of the sleeve.

It will be noted that the plate 422 has a portion extending above the ledge 424 forming a lateral stop for the package as it moves along the rails.

Means for Intermittently Advancing the Article Along the Rails

The mechanism for intermittently advancing the article along the rails R is best shown in FIGS. 22, 23, and 24. There are two sets of chains, one set comprising upper and lower chains 440 and 441, respectively. These are associated with the rail sections 420.

The chain 440 is trained around sprockets 442 and 443 mounted on stud shafts 444 and 445, respectively, the latter being carried in the sub-frame member 423. The member 423 is attached to a cross member 450 of the sub-frame by angle member 451 (see FIG. 22).

Chain 441 is similarly trained around sprockets 452, 453 carried on stub shafts 454, 455, the latter being supported by the sub-frame member 423.

Associated with the rail section 421 are two sets of chains similar to the chains and sprockets described in connection with the rail section 420, for which reason like numbers primed will be given. It will be understood that member 423', which carries the various stub shafts on which such sprockets are mounted, moves toward and away from the fixed rail 420 when rail 421 is so moved through means of handwheel G.

Member 450 of the sub-frame forms a support for member 423' through the medium of the engaging roller 450' (see FIG. 22).

The drive for the chains 440—441, 440' and 441' is from the main drive shaft 227 through chain 460, sprocket 461 mounted on cross shaft 462, the latter mounted for rotation in fixed parts of the main frame. Fixed to rotate with shaft 462 is a larger sprocket 463. Trained around sprocket 463 is a chain 464 which is also trained around a sprocket 457 mounted to drive shaft 458.

A chain 465 is trained around sprocket 466 on shaft 458, sprocket 467 on stub shaft 454, and another sprocket 468 on stub shaft 445.

By the means just described, the chains 440 and 441 are driven at the same speed and in the same direction.

There is associated with each chain 440 and 441 an elongated feed bar 470 as shown in perspective in FIG. 24, having upturned front and rear end portions 471 and 472, respectively. Adjacent the front end is a depending arm 473.

As is shown in FIG. 23, the depending arm 473 of the feed bar associated with the chain 440 is pivoted to a link of the lower chain 441 at 475 and to the upper chain at 476. Because of this arrangement, the depending arm 10 passes around sprocket 453 at the end of its advancing movement so that when returning it moves along the lower pass of chain 441, one return position being shown by dotted lines in FIG. 23.

Also in the course of such movement, portions 471 and 472 will project above the plane of the rails 420 and 421 so that lug 472 serves to advance the package from the position marked 1st to the position marked 2nd and the lug 471 advances a package which is at the position marked 2nd to the continuously operating discharge conveyor.

Associated with the rail 421 is a similar feed bar similarly connected to chains corresponding to the chains 440 and 441 which are associated with the rail 420.

It should be understood that longitudinal sealing takes place when the package is in the position marked 2nd at which time the package is at rest, the cross sealing having taken place before lug 472 engages the package.

Wrapper-Shrinking Chamber and Means for Moving and Discharging Wrapped Package

This mechanism is best shown in FIGS. 3, 4, 5, 22, and 23.

Heat chamber 480 is mounted on the rear end part 481. This heat chamber may be conventional in construction, 35 having heating means and mechanism to blow the heated air onto the wrapped package, the film of the package being thus caused to shrink to effect a tighter wrap.

For moving the package through the chamber 480 to a point of discharge at the right-hand end of FIG. 3 is an endless conveyor 482 comprising a plurality of endless chains 483 operating over sprockets 484 mounted to rotate with shaft 485. The chains are also trained over sprockets 486 on shaft 487.

For driving chains 483 there is provided a motor 490, 45 driving shaft 485 through reduction gearing 491, chain 492 and sprockets 493 and 494.

The front and rear ends of the heat chamber are substantially closed by curtain members 480' which hang loosely so that they may be brushed aside by the packages as they enter and leave the heating chamber.

Further Comments

In the explanation of the details of the invention it has been assumed that the wrapping material is in the form shown in FIG. 21 in which the sections 108, 109 result from the folding of the wrapping material to form the hinge portion 107. When this form of wrapping material is used the wrapped package appears as shown in FIGS. 26, 27 and 28 in which there is but one longitudinal seal LS opposite the fold 107 and two cross seals CS at the ends of the package.

In FIG. 25 the product or article to be wrapped is designated PA as shown between the separator plates and the packages in advance of the separator plates, whether 65 completely sealed or not, have been designated by the reference WP.

It has previously been explained that the wrapping material may be of the form shown in FIG. 29 in which there are two separate sections 108' and 109' without the hinge portion 107 which is found in the form shown in FIG. 21. When the wrapping material is in the form shown in FIG. 29 the completed package will appear as in FIG. 30 in which there are two longitudinal seals LS as well as two cross seals CS. In the machine described 70 means have been shown for forming a longitudinal seal 75

along but one edge of the package. However, when the wrapping material is in the form shown in FIG. 29 an additional longitudinal sealing means is provided at the opposite side of the machine so that as the enveloped articles advance the sections of wrapping material are longitudinally sealed along two margins.

In the specification, reference has been made to inserting a single article into position between the separator plates, but it should be understood that several articles may be inserted at the same time as a unit. Hence, in the claims, the term article or product, when used, is to be construed as one or more articles or products.

In the specification reference has also been made to the rolls of wrapping material being of different widths. That is the form which will be used in most instances. However, there may be instances when the material widths may be the same and in which the materials of the different supplies may differ in some characteristics such, for example, as color or may have different qualities each best adapted to the wrapping of a special product such as meat, fowl, fish, fruit, hardware items, etc.

Referring particularly to FIG. 11, it should be mentioned that roller 255, which is carried by member 254, is held in contact with cam 240 by means of spring 254'. Spring 254' is connected at one end to bracket 239' rising from the gear reducer 239, and at the other end to member 254 between pivot 256 and roller 255.

Referring particularly to FIGS. 13, 14, 15, and 16, reference should be made to certain parts which cause movement of other parts when the sub-frame is being moved in or out for adjustment purposes.

On that side of the member 133 adjacent the operator's side structure is provided forming a longitudinal slot 133'. Fixed to the adjacent edge of member 149 is one leg 149' of a U-shaped bracket 149a the other and shorter leg 149b of which enters the slot 133' from below. Thus, when the member 149 moves inwardly the leg 149b pushes against the member 133 and moves the same longitudinally of the shaft 151. Also when member 149 is moved outwardly the member 133 will be pulled toward the operator's side of the machine. This action is necessary because the member 153 does not move laterally.

We claim:

1. In a machine for wrapping articles, the combination of a plurality of means, each formed and adapted to hold in spaced article-receiving relation sections of limited portions of a different one of a plurality of supplies of wrapping material, means for supporting each said supply of wrapping material with a limited portion of each supply so positioned that sections of such limited portions are operatively disposed with respect to the first-mentioned means with which the particular material supply is associated, and means for moving each of said first-mentioned means and that portion of the wrapping material associated therewith into and away from article receiving position.

2. In a machine for wrapping articles with wrapping material having different characteristics, the combination of a plurality of means, each formed and adapted to hold in spaced article-receiving relation sections of limited portions of a different one of a plurality of supplies of wrapping material each having different characteristics, means for supporting each said supply of wrapping material with a limited portion of each supply so positioned that sections of such limited portions are operatively disposed with respect to the first-mentioned means with which the particular material supply is associated, and means for moving each of said first-mentioned means and that portion of the wrapping material associated therewith into and away from article-receiving position.

3. In a machine for wrapping articles of different sizes, the combination of a plurality of means, each formed and adapted to hold in spaced article-receiving relation sections of limited portions of a different one of a plurality of supplies of wrapping material of different widths, means for supporting each said supply of wrapping material with a limited portion of each supply so positioned that sections of such limited portions are operatively disposed with respect to the first-mentioned means with which the particular material supply is associated, and means for moving each of said first-mentioned means and that portion of the wrapping material associated therewith into and away from article-receiving position.

4. In a machine for wrapping articles, the combination of a plurality of means, each formed and adapted to hold in spaced article-receiving relation sections of limited portions of a different one of a plurality of supplies of wrapping material, means for supporting each said supply of wrapping material with a limited portion of each supply so positioned that sections of such limited portions are operatively disposed with respect to the first-mentioned means with which the particular material supply is associated, means for moving each of said first-mentioned means and that portion of the wrapping material associated therewith into and away from article-receiving position, and means for transversely sealingly uniting transverse sections of the material adjacent to but forwardly of said means when any of said means is in article-receiving position.

5. In a machine for wrapping articles the combination of a plurality of pairs of upper and lower separator plates, means for supporting a separate supply of wrapping material for each pair of plates, each said supply comprising two sections, one for placement on the outer face of an upper separator plate and the other on the outer face of a lower separator plate of a given pair so that each pair of separator plates and associated wrapping material is always in condition for a wrapping operation when moved to operative position, and means for moving any selected pair of separator plates and the wrapping material sections associated therewith into and away from operative position.

6. The arrangement set forth in claim 5 plus means for cross-sealingly uniting sections of wrapping material adjacent to but in advance of the forward edges of the separator plates so that there will be a cross-sealed zone in advance of each pair of separator plates whether in wrapping position or removed therefrom.

7. The arrangement set forth in claim 6 plus means for uniting longitudinal margins of the wrapper sections along at least one longitudinal margin, heat means for shrinking the wrapping material around the wrapped article, and means for advancing the wrapped article through the shrinking means.

8. The arrangement set forth in claim 7 plus means for mechanically tensioning the wrapping material about the article prior to the passage of the wrapped article through the heat shrinking means.
